LEIGH R. EVANS, OF ROCHESTER, NEW YORK, ASSIGNOR TO CYCLEMOTOR CORPORATION,
OF ROCHESTER, NEW YORK, A CORPORATION OF NEW YORK.

GASOLENE-TANK FOR MOTOR-CYCLES.

1,263,049.

Specification of Letters Patent. Patented Apr. 16, 1918.

Application filed December 18, 1915. Serial No. 67,694.

To all whom it may concern:

Be it known that I, LEIGH R. EVANS, a citizen of the United States, and a resident of the city of Rochester, in the county of Monroe and State of New York, have invented a new and useful Gasolene-Tank for Motor-Cycles, of which the following is a specification.

This invention relates to receptacles or tanks, and more particularly to tanks which are attached to the frames of bicycles and motorcycles, and which are used for holding gasoline or oil.

One of the objects of this invention is a tank which possesses great strength and rigidity and yet is light, and which can be cheaply made and assembled.

A further object of the invention is a simple cap for the filling tube of the tank which can be used to measure oil or any other substance which it is desired to add to the gasoline in a certain proportion.

A further object of the invention is to provide a vent opening for the tank which prevents the leakage or overflow of gasoline from the tank, while at the same time permitting the air to have free access to the tank.

Other objects and advantages will appear as the description of the invention progresses.

The invention consists in the parts and in the combinations and arrangements of parts, which are more fully described hereinafter.

In the accompanying drawing, in which is illustrated the preferred physical embodiment of the invention and in which like reference characters refer to like parts throughout the several views, Figure 1 is a top plan view of a gasolene tank embodying the invention, a portion of the tank between its middle and one of the ends being broken away on account of the limited space; Fig. 2 is a side view of the tank, also broken away; Fig. 3 is a transverse section taken substantially on the line 3—3 in Fig. 2; Fig. 4 is a transverse section taken substantially on the line 4—4 in Fig. 2; and Fig. 5 is an enlarged vertical section through the filling tube and filler cap, showing the vent opening.

Referring to the accompanying drawing, in the particular embodiment of the inven-

tion illustrated, the gasolene tank comprises two counterpart sections A and B, each made of a single piece of pressed sheet metal; and these sections A and B have their edges telescoped slightly and soldered, or otherwise fastened so as to be liquid tight, the edge portion of one of the sections, B, being offset slightly, as indicated at 4, Figs. 1, 3 and 4, so as to permit of this telescoping and at the same time leave the major portions of the sections lying in corresponding planes. Each of the sections A and B are rounded on each edge and corner, as clearly shown in the drawing, so as to afford a very stiff and light construction. The lower portions of the sections A and B, which constitute the bottom of the tank, incline inwardly and downwardly from their ends to a middle flat portion 5 having a hole 6 therein, as shown to the best advantage in Fig. 3. Over this hole 6 is riveted and soldered a sediment cup 7, having a removable plug 8 in its bottom for cleaning purposes. A suitable shut-off valve or cock 9 is screwed into the sediment cup 7 a short distance from its bottom; and secured to the valve 9 is a gasolene pipe 10 which leads to a carbureter in the usual way.

The tank is designed to be attached to the horizontal reach bar of a bicycle of ordinary construction or to the frames of motor cycles and the like, and for this purpose a pair of supporting clips 11 are riveted to the top of the tank near each end, diamond-shaped reinforcing plates 12 being disposed on the under side of the top and having the rivets passed through them; and each of these supporting clips 11 has a hole 13 in it near its upper end adapted to receive a bolt (not shown) for clamping that clip 11 and its mate to the reach bar of a bicycle, or to any other similar member.

A reinforcing member 14 extends from the top to the bottom of the tank for the greater part of its length between its ends, said reinforcing member having a flange 15 along each edge which is riveted to the top and bottom of the tank, respectively; and in the lower edge of the reinforcing member at the points where the middle horizontal portion 5 of the bottom of the tank and in-

clined portions of said bottom meet are cut V-shaped notches 16, as shown in dotted lines in Fig. 2. These notches 16 break the continuity of the lower edge of the reinforcing member 14, thereby permitting the flange 15 to be bent along its lower edge without difficulty; and these notches 16 are also cut deep enough to afford openings for gasoline to pass from one side of the reinforcing member 10 to the other, thereby preventing some of the gasoline from being trapped on the side of the reinforcing member opposite to the side where the discharge opening 6 is located.

The tank is filled through a filling tube 17 which is riveted and soldered to the top of the section A, and which has external screw threads formed near its top. A vertical groove 18, substantially V-shape in cross section, is cut in said screw threads of the filling tube 17, slightly deeper than the depth of said threads, as shown to the best advantage in Fig. 5, for the purpose hereinafter explained; and in the upper edge of the filling tube, preferably diametrically opposite 25 to the groove 18 is cut a shallow notch 21, as shown in Fig. 3. The filler cap 19 has a downwardly projecting annular flange having internal screw threads formed therein arranged to engage with the screw threads 30 formed on the filling tube 17. To the underside of the filler cap 19 is fastened a tube 20 which extends downwardly into the tank when the filler cap 19 is in place; and when the filler cap 19 is removed and inverted, the tube 20 can be used as a measuring cup. 35 The tank is intended to be used with engines of the type which can be lubricated in whole or in part by oil mixed with the gasoline; and to facilitate the mixture of the oil with the gasoline in the right proportions the 40 measuring tube 20 is provided, it being intended that this tube should be filled a certain number of times for each tankful of gasoline.

Referring more particularly to Fig. 5, the groove 18 through the screw threads on the filling tube 17 and the notch 21 therein form a vent opening for the tank when the filler cap 19 is screwed in place, said vent opening 45 being partly obstructed by the screw threads on the filler cap 19; and in effect these screw threads on the filler cap extend partway across the groove 18 and act as baffle plates to impede any sudden expulsion of air or 50 gasoline from the tank. A gasoline tank carried on a motorcycle is subjected to severe jolting and vibration, the tank being alternately collapsed and expanded to a slight extent, so that the gasoline is violently agitated and slopped around, and at times ex- 55erts considerable pressure against the top; and with an ordinary vent hole, regardless of how small it is, there is bound to be some leakage of the gasoline. In the construction 60

embracing this invention, however, the gasoline to escape through the vent opening must pass along the space between the outside of the tube 20 and the inside of the filling tube 17, then upon reaching the filler cap 19, abruptly change the direction of its 65 movement, pass through the notch 21 and halfway around the filler cap 19, and finally pass through the groove 18, which is partly obstructed and which has extending out into it a series of baffle plates formed by the 70 threads on the filler cap 19.

The size of the groove 18, together with the baffle plate action of the screw threads of the filler cap 19, makes the passageway 75 practically impassable for sudden spurts of 80 gasoline; and any slight dripping of the gasoline from the under side of the filler cap results in the gasoline being spread out over the extensive surface afforded by the screw threads of the filler cap, thereby enabling the inflowing air to evaporate this film of gasoline and return it to the tank. 85 This is the action which I believe explains why actual trial has demonstrated that the construction shown and described so effectively 90 prevents the escape of gasoline, while at the same time permitting the free access of air; but I do not wish to be bound by this theory of action.

In assembling the parts of the tank, the 95 clips 11, the filling tube 17, and the sediment cup 7 are riveted and soldered in place, and this operation is materially facilitated by reason of the fact that the tank is made of two sections. After these parts have been 100 fastened in place, the reinforcing member 14 is fitted and riveted in the section B; and then the section A is fitted into the section B, and soldered or otherwise fastened to said section, the reinforcing member 14 facilitating 105 this operation by keeping the edges of the two sections A and B in close contact. In this way the tank can be very quickly and cheaply assembled.

The strength of the tank is increased without adding to its weight by the rounding of all corners and edges, and by the reinforcing member 14, the whole structure forming a container of great strength and rigidity compared with its weight and one which can be 110 utilized as a gasoline tank for vehicles and for other purposes where such tanks are subjected to severe stresses and vibration.

Obviously various changes may be made in the particular construction shown and described without departing from my invention, and I do not wish to be restricted to the details of this construction shown and described.

What I claim is:

A gasoline tank comprising two counter-part elongated sections having their corresponding edges overlapped and joined to-

gether by a liquid tight joint to form a closed receptacle, a filling tube riveted to one of said sections, a discharge tube riveted to one of said sections, and a longitudinal reinforcing member extending between opposite walls of said tank and fastened thereto for spacing opposite walls of said

tank apart and for tying them together, said reinforcing member having holes therein for permitting gasolene to flow from one side of said reinforcing member to the other, the edges and corners of said sections being rounded.

LEIGH R. EVANS.
